UNITED STATES PATENT OFFICE.

ERNST RUTTMANN, OF STUTTGART, GERMANY.

RICOCHET BALL GAME.

Application filed August 24, 1921. Serial No. 494,848.

To all whom it may concern:

Be it known that I, ERNST RUTTMANN, a citizen of the Republic of Germany, residing at Stuttgart, Wurtemberg, Germany, have 5 invented certain new and useful Improvements in Ricochet Ball Games (for which I have filed an application in Germany on April 29, 1919), of which the following is a specification.

10 This invention relates to a ball game in which the ball is made to rebound from a surface which has been suddenly stretched. The ends of the surface are fixed to handle levers. When the handles of the levers are 15 suddenly brought close together the ricochet surface is stretched and throws the ball up.

With the games of this type of known construction the hand levers are arranged so that both hands are required for the 20 manipulation. This is however inconvenient for several reasons. The simultaneous handling of the two levers with both hands requires that the arms be stretched forward so that the jumping for catching the ball is 25 rendered insecure and the player comes frequently to fall.

This invention avoids these inconveniences and permits an elegant playing of the game. This effect is due to the special arrangement 30 and construction of the hingedly connected levers in such a manner that the handles of said levers can be gripped with one hand so that only one hand is occupied when the game is being played. In this manner the 35 game can be played elegantly and gracefully, the free movements of the player being not impeded in the least. The reaching range is thus much larger than when the device is held with both hands.

40 In order that the invention may be clearly understood, I shall proceed to describe the same with reference to the several forms of construction shown by way of example on the accompanying drawing, wherein:—

45 Figs. 1, 2, 3, 3^a and 4 show each perspective a separate form of construction.

In the form of construction Fig. 1 the net *n* is fixed with its longitudinal sides directly on the rods *a'* and *a²*. These rods *a'* 50 and *a²* are constructed like double armed hand levers *g* and terminated by handles *b* which are placed so closely the one to the other that they can be gripped with one hand to be pressed the one against the other. 55 They are pivotably mounted in proximity of the handles *b* upon bolts *e* of a cross piece *d*

so that the levers at the ends of the net are spread out when the handles *b* are pressed together. The net *n* is thus stretched and the ball *c* placed upon the same is thrown up. 60 To return the rods *a'* and *a²* to the initial position a spring *f* of convenient construction is provided. The device of this form of construction is held horizontally.

Fig. 2 shows a form of construction in 65 which the device has to be held vertically. Instead of the net a cloth *n* is provided whose longitudinal sides *a* are attached to parallel rods *a'* and *a²*, said rods being supported by handles *g* which correspond with 70 the lower parts *g* of the rods *a'* and *a²* of the form of construction shown on Fig. 1. The arrangement is otherwise the same as described with reference to Fig. 1.

The form of construction Fig. 3 comprises 75 a triangular net *n* whose one side is attached to the rod *a'*. The rod is supported by a rod *g*. The point of the net end is attached directly to the end *a²* of the hand lever. In this form of construction only the hand lever *g* to which the point of the net is attached is pivotable around an axle *e* fixed 80 upon the cross piece *d* projecting from the vertical rod *g*.

The form of construction Fig. 3^a differs 85 from that Fig. 3 only in so far that the rod *a'* is curved to a semicircle so that the net *n* forms a conical trough from which the ball cannot drop out as easily as from the flat net *n* Fig. 3.

90 Fig. 4 shows a form of construction which in general is similar to that of Fig. 2. The rods *a'* and *a²* are however bent to U-shape or curved semi-circularly so that when the cloth *n* is stretched a kind of trough is 95 formed which prevents the ball *c* from dropping out. The cross piece *d* is divided and each half of the same is fixed to the lower end of one of the levers *g*, a hinge which connects the two parts of the cross piece *d* serving as pivot. The hinge being 100 fixed to the lower edge of *d*, the upper edge of *d* acts as a means to limit the coming together of the ends of the levers. Separate handles *b*, *b* are fixed one to each part 105 *d* of the cross piece.

The form and the construction of the ricochetting surface *n*, of the rods *a'* and *a²*, of the hand levers *g* and the other parts 110 can be modified according to requirement without departing from the idea of the invention.

I claim:—

1. A device for playing ricochet ball comprising the combination of two hand-levers, a slack ricochetting surface of mesh material secured at its respective ends to the upper ends of said levers, means for pivotally connecting said levers to each other near their lower ends, handles at the lower ends of said levers, limiting means to prevent the upper ends of the levers coming into too close proximity with each other, and spring means to return the levers to their initial position when the handles are released, the pivotal connecting means being at such distance from the lower ends of the levers that the handles may be gripped with one hand.
2. A device for playing ricochet ball comprising the combination of two hand-levers, a slack ricochetting surface of convenient material secured at its respective ends to

the outer ends of said levers, handles at the lower ends of said levers; a divided cross-piece half of which is secured near the lower end of each lever, means for pivotally connecting the halves of the cross-piece at the lower edge of the same, and spring means to maintain the levers in their initial position when the handles are released, the divided cross-piece acting as a limiting means to prevent the ends of the levers coming into too close proximity with each other and the cross-piece being located at such distance from the lower ends of the levers that the handles may be gripped with one hand.

In testimony whereof I affix my signature in presence of two witnesses:

ERNST RUTTMANN.

Witnesses:

E. SCHLEICHER,
FREDA BLAILIVER.
